UNITED STATES PATENT OFFICE.

FRANK H. SCHWERIN, OF WEST VIEW, PENNSYLVANIA, ASSIGNOR TO THE DUFF
MANUFACTURING COMPANY, OF PITTSBURGH, PENNSYLVANIA, A CORPORATION
OF PENNSYLVANIA.

SILL STRAIGHTENER.

Application filed August 25, 1923. Serial No. 659,268.

To all whom it may concern.

Be it known that I, FRANK H. SCHWERIN, a citizen of the United States, and a resident of the borough of West View, in the 5 county of Allegheny and State of Pennsylvania, have invented a new and useful Sill Straightener, of which the following is a specification.

The subject of the invention is a tool 10 particularly for straightening the center sills of freight-cars, which frequently become bent and the straightening of which heretofore has been a laborious and lengthy matter. The object is to provide an implement of simple and strong construction 15 and moderate weight, convenient to use, having a narrow minimum and an ample maximum spacing, adapted for both forcing apart and drawing inward on the bent sills, 20 and applicable, removable, operable, and directly changeable from one operation to the other as required, all in the most convenient manner.

In the accompanying drawings forming a 25 part hereof:

Figure 1 is a side elevation of the device in position to draw inward on a pair of car sills;

Fig. 2 is a similar view, showing the nut-travelers turned upside down with reference 30 to Fig. 1 and in position to act to spread a pair of sills; and

Fig. 3 is a perspective view of one of the nut-travelers.

One part of the tool is a stout screw-bar 1, 35 the two parts 2, 2 of which, extending oppositely from the central portion, are reversely screw-threaded, the thread in one part being right-hand and in the other part left-hand. Fixed on the center of the bar is 40 a ratchet-wheel 3, while swung on this part of the bar is a lever-socket and pawl-case 4 containing a pawl to engage with and turn the ratchet.

On the parts 2, 2 of the screw are duplicate but reversely positioned nut-travelers 5, 5. These have a central opening through them, threaded to engage the threads of the screw, which passes through the travelers.

On one side of each traveler is a flat bearing face 6, parallel with the axis of the screw; and projecting laterally from the traveler and occupying about half its length is a buttress 7; the working face 8 of which 55 forms an approximately square internal

angle with the face 6. The buttresses of the two travelers face away from each other.

At the opposite side of each traveler is another side bearing face 9, which is overhung by a flat jaw 10, leaving a slotted recess 11 lying substantially parallel with the axis. This jaw originates from the body of the traveler at the opposite end or half from the buttress 7, so that the jaw and buttress are longitudinally offset and face reversely with respect to each other.

The two remaining sides of each traveler may be utilized for chain-hooks 12, which face in the same direction as the jaw of the traveler and reversely to the buttress.

Fig. 2 shows the jack in position for forcing outward on the center sills of a car at one point, the buttresses being introduced between the channel sills, with their faces 8 against the backs of the channels and their faces 6 against the faces of the flanges. It will be noted that the angle between the faces 6 and 8 is a little less than a right angle, the face 8 being slightly inclined from the perpendicular to the axis of the screw; so that the buttress will thrust first at the tip, or at a point away from the base, so that any springing of the screw will be counteracted and a full purchase be insured.

By simply turning the travelers upside down in the views, and running them out or in, their action can be changed from spreading to drawing in, and vice-versa. Fig. 1 shows them applied for forcing the sills inward. The bottoms of the flanges of the sills bear upon the faces 9, and the flanges are overhung by the jaws 10, the backs of the recesses 11 at the bases of the jaws thrusting against the edges of the flanges.

In this way the sills of a car can be readily straightened by thrusting them apart at one or more points, and drawing them together at one or more other points, as may be required. Notwithstanding that the stresses are entirely eccentric to the screw, and are severe, the action is very effective.

The device, either in the precise form or in modified form, may also be used for other similar purposes. A tool of this character may be employed to advantage for spreading railroad ties in the ballast.

The chain-hooks 12 are serviceable, in connection with chains (not shown), for pulling in the bulged sides of freight cars.

What I claim as new is:

5 1. A device of the character described comprising a right- and left-hand screw bar with ratchet-lever means on the central part of the bar, and two nut-travelers on the reversely threaded halves of the bar, said 10 travels being formed each with a buttress projecting laterally from one side of the traveler forming an approximately square internal angle therewith, and with a jaw overhanging the other side so as to leave 15 a slotted recess, the buttresses facing outwardly away from the central part of the bar and the jaws facing inwardly toward each other, whereby the device is adapted to act outwardly between, and inwardly on 20 the flanges of, a pair of channel sills, to straighten the same.

2. As an article of manufacture, the here-

in described block having a screw-threaded opening therethrough, a flat bearing face on one side, a flat-faced buttress projecting from said side forming approximately a square angle with said bearing face, and an overhanging jaw on the opposite side of the block forming a slotted recess, the buttress and the jaw facing reversely to each other. 25

3. As an article of manufacture, the herein described block having a screw-threaded opening therethrough, a flat bearing face on one side, a flat-faced buttress projecting from said side forming approximately a square angle with said bearing face, an overhanging jaw on the opposite side of the block forming a slotted recess, the buttress and the jaw facing reversely to each other, 30 and chain hooks on the two other opposite sides of the block facing in the same direction as the jaw. 35

FRANK H. SCHWERIN.
